Des. 228,741
Patented Oct. 23, 1973

228,741

COMBINED JUG AND CAP THEREFOR

Christian Andersen Holme, Albertslund, Denmark, assignor to Colgate-Palmolive Company, New York, N.Y.

Filed Dec. 29, 1971, Ser. No. 213,794

Claims priority, application Denmark July 30, 1971

Term of patent 14 years

Int. Cl. D9—01

U.S. Cl. D9—43

FIG. 1

FIG. 3

FIG. 2

FIG. 4

FIG. 5

FIG. 6

FIG. 1 is a perspective view of a combined jug and cap therefor embodying my new design;

FIG. 2 is a top plan view thereof;

FIG. 3 is a side elevational view thereof showing the side not visible in FIG. 1;

FIG. 4 is an end elevational view thereof as seen from the left of FIG. 3;

FIG. 5 is an end elevational view thereof as seen from the right of FIG. 3; and

FIG. 6 is a bottom plan view thereof.

I claim:

The ornamental design for a combined jug and cap therefor, as shown.
